UNITED STATES PATENT OFFICE

2,453,307

ROOF FOR RAILWAY FREIGHT CARS

Tony Despotakis, Hyde Park, Pa., assignor to Standard Railway Equipment Manufacturing Company, Chicago, Ill., a corporation of Delaware

Application March 28, 1947, Serial No. 737,819

3 Claims. (Cl. 108—5.4)

1

The invention relates to a roof for a railway freight car and has for its object to provide such a roof comprising metallic roof sheets extending crosswise of the car with the meeting sides thereof formed and capped to provide a strong seam construction in beam action between the opposite side walls of a railway car, which construction is weatherproof and so arranged that the roof sheets and caps may be easily assembled or disassembled in case repair or replacement of a roof sheet or a cap becomes necessary.

A further object is to provide such a seam construction to help resist the distortions of a car in vertical and/or horizontal planes in service and to attach such a seam construction to the opposite side walls of a car to aid in such resistance.

In the drawings:

Figure 1 is a plan view of my roof applied to a car.

Figure 2 is a side elevation of Figure 1.

Figure 3 is an enlarged longitudinal section through my roof.

Figure 4 is an enlarged section through the side plate of the car and also showing the roof sheet in section and the cap in side elevation.

Figure 5 is a side elevation of Figure 4.

Figure 6 shows an end of the cap by itself.

Figure 7 shows an end of the roof sheet by itself.

As shown in the drawings the roof comprises a plurality of roof sheets 2 extending crosswise of the car and formed with depending end flanges 3 secured to the vertical element 4 of the side plate 5 by the rivets 6.

Each roof sheet 2 is formed with upstanding side flanges 10 which when the roof sheets are applied to the car are a substantial distance from the corresponding flange 10 of the adjacent roof sheet, as shown in Figures 3 and 5. Each flange is preferably formed with a horizontal reflare 11 which overlaps the reflare of the adjacent roof sheet.

An inserted channel-shaped cap 13 straddles the upstanding flanges 10 of the adjacent roof sheets and the reflanges 11 thereof. The cap 13 terminates in a depending end flange 14 which closes the ends of the spaces 12 between the flanges 11—11 of adjacent roof sheets. The flanges of the channel-shaped caps 13 are welded to the depending flange 14 thereof, as indicated at 15, to form a closed end for the cap. The depending flange 14 extends downwardly and is secured to the side plate by the rivet 16.

The depending end flange of the cap is extended laterally (see Figures 5 and 6) to overlap

2

the end flanges of the two adjacent roof sheets to aid in bracing the car against distortion of the car due to service movements thereof.

To secure the flanges 11—11 and adjacent roof sheets together and to the cap 13 I provide a plurality of spaced horizontal rivets 18 provided with ferrules 19 to assure good rivets. (See Figure 3.)

Such a seam structure provides a strong beam between the opposite side walls of the car to support any load imposed thereon and to resist the tendency of the side plates to come together or go apart due to service movements of the car, and, furthermore, forms a good brace against diagonal distortion of the car.

15 The accompanying drawings illustrate the preferred form of the invention, though it is to be understood that the invention is not limited to the exact details of construction shown and described, as it is obvious that various modifications 20 thereof, within the scope of the claims, will occur to persons skilled in the art.

I claim:

1. A roof for a railway car having spaced side plates each comprising a vertical element and a substantially horizontal element, said roof comprising metallic roof sheets disposed crosswise of the car and formed with depending end flanges secured to said vertical elements, respectively, each roof sheet formed with upstanding side marginal flanges which are spaced a substantial distance from the corresponding flange of the adjacent roof sheet, said upstanding flanges each formed with a horizontal reflare which overlaps the reflare of the adjacent roof sheet, inverted channel-shaped caps straddling the upstanding flanges of adjacent roof sheets said caps terminating in depending end flanges which close the ends of the space between the flanges of adjacent roof sheets and extend downwardly and are secured to the vertical elements of the side plates, and means to secure the cap and adjacent roof sheet flanges together.

2. A structure defined in claim 1 including a plurality of spaced rivets extending through the cap and the flanges of adjacent roof sheets and a ferrule surrounding each rivet which extends between said adjacent flanges.

3. A structure defined in claim 1 including the depending flanges of the caps overlapping the depending end flanges of adjacent roof sheets and are secured to the side plates by the same means.

TONY DESPOTAKIS.
